APPARATUS FOR DIMPLING SHEET METAL STOCK

Arthur A. Schwartz, Buffalo, N. Y., assignor to
Bell Aircraft Corporation, Buffalo, N. Y.

Application January 27, 1945, Serial No. 574,862.

2 Claims. (Cl. 153—21)

1

This invention relates to a machining means such as is adapted to metal pressing and like operations, and more particularly to an improved means for locally dimpling sheet metal stock pieces and the like as in connection with large manufacturing operations.

One of the objects of the invention is to provide an improved means for dimpling or pressing shop stock pieces into reformed shapes. Another object of the invention is to provide an improved dimpling means such as is adapted particularly to provide improved results in connection with rapid multiple pressing operations. Another object of the invention is to provide an improved means for dimpling thermoplastic stock pieces, such as is particularly suitable for example to provide multiple local deforming operations at rapid rate.

Another more specific object of the invention is to provide an improved die type mechanism for locally dimpling cold sheet metal stock pieces and the like into reformed shapes. Another object of the invention is to provide an improved method and means for "dimpling" sheet metal stock pieces at rapid rate while reducing the stock material fracturing tendencies. Another more specific object of the invention is to provide an improved method and means for "dimpling" stock of normally nonmalleable metal such as aluminum and magnesium alloy stock sheets and the like. Other objects and advantages of the invention will appear in the specification hereinafter.

In the drawings:

Fig. 1 is a fragmentary general arrangement view of an apparatus of the invention; and

Fig. 2 is a fragmentary vertical section, on an enlarged scale, through the die portions of the apparatus of Fig. 1 showing a work sheet in operative position thereon.

The drawing illustrates a so-called "dimpling" process being applied to a work sheet designated generally at 10; the work sheet having been previously drilled as indicated at 12—12—12 so as to receive rivets or the like as in connection for example with fabrication of sheet metal skin parts for aircraft or the like. The invention is shown as being applied to the drilled work sheet 10 for the purpose of locally dimpling the work sheet at the region of each of the drilled holes so as to form a countersink thereat. Such operations are more commonly known as "dimpling," and will adapt the work sheet to receive the conically shaped heads of rivets or the like when inserted through the openings 12—12—12 in such manner that the rivet heads will be disposed flush with

2

the bottom surface of the work sheet 10 as shown in Fig. 2.

In certain arts, as for example in the aircraft manufacturing art, large quantities of multiple drilled and countersunk work sheets of the character of the work sheet 10 of the drawing are required; and such work sheets are often formed of special alloys designed to provide such sheets to be extremely light weight yet of sufficient strength and rigidity to successfully withstand the loads to be imposed thereon. Suitable alloys for such purposes usually include the aluminum and magnesium type alloys such as are relatively nonmalleable at normal temperatures. Therefore, it is difficult to "dimple" such work sheets when in "cold" condition without fracturing and tearing the stock material in the region of each dimpling operation. Yet it is undesirable to overall heat such work sheets prior to such dimpling operations because such overall heating renders the work sheets relatively soft and unstable and subject to twisting and wrinkling distortions during the handling operations incidental to transferring them from the heating operation to the dimpling operation. Also, such overall heating methods are undesirable because of the additional step involved thereby and the extra facilities required to perform such operations, and the extra time and expense incidental thereto.

The present invention obviates the objections and disadvantages referred to hereinabove by providing the work sheet to be spontaneously heated only locally exactly at the regions of the dimpling operations; the heat being thereby focalized upon only the portion or portions of the sheet required to be heated, so as to bring such portions rapidly to the optimum temperature for the dimpling operations while avoiding overall weakening of the work sheet structure.

With the above purposes in view the apparatus of the invention may comprise, as illustrated in the drawing, an upper die 16 and a punch member 24 arranged in opposing relation to receive the work sheet to be "dimpled" therebetween. Any suitable means for providing relative movement between the die 16 and the punch member 24 may be employed, but as illustrated in the drawing the upper die 16 may be carried by a ram stem 20 so as to be adapted to be alternately pushed and pulled toward and away from the punch member 24. A supporting member 18 located beneath the upper die 16 is centrally bored at 22 and slidably mounted upon the punch member. This punch member extends from a stationary base plate 26 having a threaded stub por-

tion 28 for convenient mounting upon any suitable stationary base device. A compression spring 30 is arranged between the base plate 26 and the supporting member 18 so as to normally maintain this member in spaced relation from the base plate 26 as illustrated in Fig. 2.

The punch member 24 carries integrally therewith a pilot boss 32 extending therefrom such as is adapted to be inserted through the openings drilled through the work sheet preliminary to performance of the "dimpling" operation, whereby each drilled portion of the work sheet will be automatically centralized relative to the punch member 24 when mounted upon the pilot boss 32. The upper end of the punch member 24 is conically shaped as indicated at 34 and the upper die 16 is bored as indicated at 36 to receive the boss 32 and is counterbored as indicated at 38 to complement the shape of the conical mandrel portion 34. Thus, it will be understood that upon application of power to the ram 20 the upper die 16 will be forced so as to first contact the upper surface of the work sheet 10 and then to depress the latter along with the supporting member 18 against the action of the spring 30. Since the punch member 24 is stationary the conically surfaced portion 34 thereof is thereby forced to press the material of the stock piece surrounding the aperture 12 upwardly into the countersink portion 33 of the upper die 16; thereby forming the material of the stock piece into the shape indicated at 40 in the region of the opening 12 at the right hand side of the stock piece 10. Stop blocks 42-42 may be provided to extend from the base plate 26 to limit the retrograde movement of the supporting member 18, as may be desired.

To provide local malleabilizing of the stock piece such as is required to prevent fracturing thereof in connection with each dimpling operation, the upper die 16 and the supporting member 18 are each provided with heat supply means. This may be in the form of conduits 44-46 extending gas shown through the interior of the die 16 and supporting member 18 in such manner as to encircle the stock piece shaping portion of the die 16 and the punch member 24 while being in relatively close proximity thereto; and means are provided for circulating a heating fluid medium through the channels 44-46.

For example, as illustrated in Fig. 2, the conduits 44-46 may be provided in the die and supporting member bodies by first externally grooving the latter and then enclosing the grooved surfaces thereof by means of metallic sleeves 48-48 which may be sweated or otherwise mounted thereon in fluid leak-proof manner. Heat insulating sheathes 50-50 of asbestos or the like may be wrapped about the sheathes 48-48, and heating fluid inlet-outlet conduits 52-54 are connected in open communication with the corresponding channeled portions 44-46. The conduits 54-54 lead from a single heated fluid supply manifold 55 (Fig. 1), and the conduits 52-52 lead to a common fluid discharge manifold 56. Heating elements such as illustrated at 58-58 may be arranged in conjunction with the hot fluid manifold 55, and may comprise any suitable heating devices such as electrical heating means controlled by rheostats as indicated at 60-60. The manifold 55 is illustrated as being arranged to be fed with a supply of compressed air at 62, and the air discharge conduit 56 may be returned as indicated at 64 into open communication with a jacket 65 surrounding a portion of the compressed air conduit 55 for preheating the latter,

thus effecting substantial saving in the operation required of the heating elements 58-58. The hot air jacket 65 exhausts into the atmosphere as at 66.

5 Thus, it will be understood that immediately upon mounting the stock piece in operative position upon the supporting member 18 the heat emanating therefrom will permeate the stock piece in the immediate region of contact with the punch member where the dimpling operation is commenced. Similarly, upon initial contact of the heated upper die 16 with the stock piece, a heat transfer operation in the stock piece will be set up in the immediate region where the dimpling operation is to be performed. Then as the die jaws squeeze down upon the stock sheet the dimpling operation will be accompanied by further heat transfer effects such as will bring that portion of the stock piece which is being forged to the desired malleabilizing temperature. Thus, a particular feature and advantage of the invention is that each local heating operation is performed automatically without attention by the operator and in exact synchronism with each local dimpling process, whereby the work sheet may be momentarily brought up to optimum forging temperature without requiring an undesirable elongation of the maximum heating period.

I have determined that heated air may be used 30 with particular advantage for the die heating medium as illustrated and described hereinabove whenever the stock pieces being fabricated are of relatively thin sheet and rapid heat transfer form. It seems that the use of hot air for this 35 purpose makes it possible to provide extremely flexible temperature control such as to almost spontaneously procure optimum dimpling temperatures at the areas to be forged while avoiding producing annealing temperature conditions 40 in the stock sheets such as would adversely affect the stock sheets for the purposes for which they are intended.

Although only one application of the method of the invention and only one form of the apparatus 45 thereof have been illustrated and discussed in detail, it will be understood that the invention is also applicable to various other manufacturing operations and that various changes may be made 50 in the apparatus as disclosed herein without departing from the spirit of the invention or the scope of the appended claims.

I claim:

1. An apparatus for dimpling preperforated sheet metal stock, comprising an upper die formed 55 with a counterbore and an associated countersunk portion, a punch member having a pilot for successive engagement with the apertures of the stock, said punch member also having a conically surfaced portion for cooperation with the countersunk portion of the upper die, means for moving said die and said punch member toward each other to perform a dimpling operation on the interposed stock around the engaged aperture thereof, a workpiece supporting member slidably 60 carried by said punch member, said upper die and said supporting member each being formed with an external annular groove, an annular metallic sleeve permanently secured to said upper die, an annular metallic sleeve permanently secured to said member, said sleeves serving to enclose the annular grooves in said die and said member to form circulating channels for heated compressed air, an inlet conduit and an outlet conduit carried by said upper die and said member for conducting heating medium to the 65 70 75

grooves thereof, an inlet manifold connecting said inlet conduits, an outlet manifold connecting said outlet conduits, means for heating compressed air supplied to said inlet manifold, and a jacket connected to said outlet manifold, said inlet manifold passing through said jacket to preheat the air supplied to the heating means.

2. An apparatus for dimpling sheet metal stock, comprising a die formed with a countersunk portion, a punch member having a conically surfaced portion for cooperation with the countersunk portion of the die, means for moving said die and said punch member toward each other to perform a dimpling operation on the interposed stock, a workpiece supporting member slidably carried by said punch member, said die and said supporting member each being formed with an external annular groove, an annular metallic sleeve permanently secured to said die, an annular metallic sleeve permanently secured to said member, said sleeves serving to enclose the annular grooves in said die and said member to form circulating channels for heated compressed air, an inlet conduit and an outlet conduit carried by said die and said member for conducting heating medium to the grooves thereof, an inlet manifold connecting said inlet conduits, an outlet manifold connecting said outlet conduits, an outlet manifold connecting said outlet conduits, means for heating compressed air supplied to

said inlet manifold, and a jacket connected to said outlet manifold, said inlet manifold passing through said jacket to preheat the air supplied to the heating means.
